INFLATABLE SPACE CAPSULE TOY

Jules Cotler, New York, N.Y. (105-05 69th Ave.,
Forest Hills 75, N.Y.), and Jerome H. Lemelson,
8B Garfield Apts., Metuchen, N.J.

Filed Mar. 7, 1962, Ser. No. 69,130

Term of patent 14 years

(Cl. D34—15)

Fig. 2

Fig. 1

FIG. 1 is a front elevational view of an inflatable space capsule toy showing our new design; and
FIG. 2 is a top plan view thereof.

We claim:

The ornamental design for an inflatable space capsule toy, substantially as shown.
